UNITED STATES PATENT OFFICE

PAUL H. CRAGO, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY CAR RETARDER

Application filed January 16, 1932. Serial No. 587,076.

My invention relates to railway car retarders of the type involving means located in the trackway for cooperation with the wheels of a moving car to retard the motion of the car. More specifically my invention relates to retarders of the type shown and described in Letters Patent of the United States No. 1,812,190, granted to Wolfgang Baseler on June 30, 1931. One feature of my invention 10 is the provision, in retarders of the type shown in the Baseler patent, of means for passing electric current through the wheels of a car for cooperation with the magnetic flux produced by the retarder magnets to increase the retarding effect on the car.

I will describe one form of apparatus embodying my invention, and will then point out the novel features thereof in claims.

In the accompanying drawing, Fig. 1 is a 20 transverse sectional view showing one form of retarder embodying my invention. Fig. 2 is a side view of the retarder shown in Fig. 1. Similar reference characters refer to similar parts in each of the views.

25 Referring first to Fig. 1, the reference characters R¹ and R² designate the track rails of a railway track. Associated with the track rail R¹ is a U-shaped electromagnet B¹, the legs of which are located on opposite sides of the rail and the pole pieces 5 of which are so disposed as to cooperate with the opposite faces of a car wheel W¹ traveling on the rail. The magnet is provided with the usual energizing winding A¹. The magnet is preferably so arranged that the pole pieces 5, 5 30 may move toward and away from each other, and so toward and away from wheel W¹, according as the magnet is energized or de-energized as shown in the above mentioned Baseler Patent No. 1,812,190. As here shown, 40 these pole pieces are arranged to slide horizontally on the two legs of the magnet. Other means may be provided, however, for permitting the pole pieces to move toward and away from the wheel W¹.

A similar magnet B² is associated in a similar manner with the track rail R², and the two magnets B¹ and B² are oppositely disposed so that they cooperate simultaneously with the two wheels on a given axle D.

The windings A¹ and A² are supplied with alternating current from the secondary of a transformer F, the primary of which is at times connected with a suitable source of current which is not shown in the drawing. 55

As shown in Fig. 2, the retarder will usually comprise a plurality of electromagnets B¹ or B² disposed along each track rail in parallel relation, the pole pieces 5 being common to all the magnets, so that these pole pieces constitute braking bars for cooperation with the wheels of a car passing through the retarder. 60

As thus far described, the retarder is similar to that shown in the Baseler patent referred to hereinbefore. In accordance with 65 my invention I connect a source of current across the two rails R¹ and R² for the purpose of producing current in the car wheels to cooperate with the magnetic flux produced by the magnets B¹ and B². As here shown, 70 this source of current is the secondary of a transformer E, the primary of which is at times connected with a source of alternating current which is not shown in the drawing. One terminal of the secondary of this transformer is connected with rail R¹, and the other secondary terminal is connected with rail R². It follows that when an axle and pair of wheels occupy the retarder, current 75 will flow from the left-hand terminal, for example, of the secondary of transformer E, through rail R¹, wheel W¹, axle D, wheel W², and rail R² to the right-hand terminal of the secondary of transformer E.

As shown in Fig. 1, the flux due to magnet 85 B¹ passes through wheel W¹ in the direction indicated by the arrow G¹, while the flux due to magnet B² passes through the wheel W² in the direction indicated by the arrow G². Furthermore, the current produced by transformer E passes through the wheels and axle in the direction indicated by the arrows 90 7. These directions of flux and current are, of course, instantaneous relative directions. When the directions of flux and current are 95 as just explained, then assuming that the car is moving toward the reader, as viewed in Fig. 1, the current in the wheels will cooperate with the flux in the wheels in such manner as to tend to retard the movement of the car. 100

The same result could be obtained by reversing the instantaneous relative direction of the flux in each magnet, and also reversing the instantaneous relative direction of the 5 current through the car wheels and axle.

It will be seen from the foregoing, that the axle D and the wheels W^1 and W^2 , moving through the retarding magnets, produce the same effect as that which would be produced 10 by moving a U-shaped wire through the length of the retarder with the two ends in contact with the two rails respectively, because current flows from one rail up to the axle and from the axle down to the other rail. 15 Since the flux path is long, the current carrying path cannot be forced completely out of the magnetic field as would be possible if a small magnetic pole were placed opposite the wheel. It is apparent that the force tending 20 to prevent the movement of the axle and wheels in a direction toward the reader as viewed in Fig. 1, is proportional to the vertical height of the magnetic field traversed by the wheel, the length of the retarder, the 25 flux density, and the current flowing in the wheels and axle; in other words, this force follows the usual laws for the force on a current carrying conductor moving in a magnetic field. The loss of efficiency, due to 30 magnetic flux flowing through the rail between the pole pieces 5 of either magnet, may, of course, be reduced to the minimum by using rails of non-magnetizable material, such for example, as maganese steel.

35 It should be noted that the tendency for the current path from point of contact of the wheel with the rail to the car axle to be forced backwardly into the rim of the wheel, is compensated by the fact that if the current were 40 flowing in the rim of the wheel, the current line would be cutting a longer magnetic path than when the current flows directly through a radial path from the point of contact to the axle. This tendency of the current path 45 to bend is therefore balanced at a point producing the least retardation. Furthermore, it will be seen from an inspection of Fig. 2 that the shortest possible path for the current through the magnetic field is the vertical 50 path, and that the current could be deviated from this path only a very little without increasing the mechanical torque available for retardation of the car.

The supply of current to the transformers 55 F and E may, of course, be controlled in any suitable manner, either manually or automatically, or both. The control of these currents forms no part of my present invention. Furthermore, the current supplied to 60 the windings A^1 and A^2 , and to the wheels and axles, may be direct current.

To produce the full retardation ordinarily desired, consideration must be given to the fact that the apparatus also produces retardation due to the eddy current effect and the

frictional effect, as set forth in the Baseler patent referred to hereinbefore. Consequently, any current which is supplied to the wheels and axle by the transformer E will provide an increased retardation over that 70 obtained with the usual eddy current brake.

One advantage of apparatus embodying my invention is that the retardation due to the current supplied to the wheels and axles 75 is independent of the speed of the car.

Although I have herein shown and described only one form of apparatus embodying my invention, it is understood that various changes and modifications may be 80 made therein within the scope of the appended claims without departing from the spirit and scope of my invention.

Having thus described my invention, what I claim is:

1. A railway car retarder comprising 85 means for passing magnetic flux through a car wheel in a direction parallel to the axle, and means for passing electric current through said wheel in a path perpendicular to the path of such flux and in such direction 90 as to coact with the flux to retard the movement of the car.

2. A railway car retarder comprising a U-shaped electromagnet located in the track-way with its legs on opposite sides of a 95 rail and its pole pieces in positions to coact with the opposite faces of a car wheel moving along such rail, and means for passing electric current through such car wheel in a direction perpendicular to the path of the 100 flux produced in the wheel by said electromagnet.

3. A railway car retarder comprising 105 means for passing magnetic flux through a car wheel in a direction parallel to the axle, and a source of electric current connected across the rails of the track traversed by the car for causing current to flow through the wheels and axles of the car in such direction as to coact with such magnetic flux to retard the movement of the car.

4. A railway car retarder comprising two 110 oppositely located U-shaped electromagnets associated with the two rails of a track respectively and each having its legs disposed on opposite sides of the associated rail and its pole pieces in positions to coact with the opposite faces of a wheel moving along the rail, and a source of electric current connected across said rails in such direction that when a pair of car wheels passes through 115 said magnets the current which flows through such wheels and the associated axle coacts with the magnetic flux produced in the wheels by the magnets to retard the movement of the car.

In testimony whereof I affix my signature.
PAUL H. CRAGO.
